UNITED STATES PATENT OFFICE.

ALEXANDRA FALBO, VICTOR FERRIS, AND ALEXANDER FERRIS, OF NEW YORK, N. Y.

DESIGN FOR A VENDING-MACHINE CASING.

Application filed May 18, 1923. Serial No. 6,210. Term of patent 7 years.

To all whom it may concern:

Be it known that ALEXANDRA FALBO, VICTOR FERRIS, and ALEXANDER FERRIS, citizens of the United States, residing at New York city, county and State of New York, have invented a new and useful Design for Vending-Machine Casing, of which the following is a specification.

Reference hereto is had to the accompanying drawings, forming part of this application in which:

Figure 1 is a perspective view of the vending machine or dispensing apparatus; and Figure 2 is a face elevation of the structure involved in the design.

We claim:—

The ornamental design for a vending machine casing as shown.

In testimony whereof we have signed our names to this specification in the presence of two subscribing witnesses.

ALEXANDRA FALBO.
VICTOR FERRIS.
ALEXANDER FERRIS.
